UNITED STATES PATENT OFFICE.

RALPH H. WEST, OF CLEVELAND, OHIO.

DESIGN FOR A VEHICLE-WHEEL.

53,544.

Specification for Design.

Patented July 8, 1919.

Application filed December 20, 1915. Serial No. 67,924. Term of patent 14 years.

To all whom it may concern:

Be it known that I, RALPH H. WEST, a citizen of the United States, residing at 805 East 70th street, in the city of Cleveland, county of Cuyahoga, and State of Ohio, U. S. A., have invented a new, original, and ornamental Design for Vehicle-Wheels, of which the following is a specification, reference being had to the accompanying drawings, forming a part thereof.

In said drawings, Figure 1 is a front elevation of a wheel showing my new design; Fig. 2 is a central section thereof.

I claim:

The ornamental design for a vehicle wheel substantially as shown.

RALPH H. WEST
